UNITED STATES PATENT OFFICE.

CARL WILHELM SCHOPPE, OF PORTLAND, OREGON.

AUTOMOBILE ACCESSORY.

1,417,416.

Specification of Letters Patent. Patented May 23, 1922.

Application filed June 27, 1921. Serial No. 480,525.

To all whom it may concern:

Be it known that I, CARL WILHELM SCHOPPE, a citizen of the United States, residing at Portland, in the county of Multnomah and State of Oregon, have invented a new and useful Automobile Accessory, of which the following is a specification.

My invention relates to improvements in automobile accessories, in which a foot mat 10 on the running board may be converted into a guard railing, in case said running board is intended to be used for carrying packages.

The objects of my invention are to furnish a mechanism which serves the purposes of 15 mat and guard railing equally well, which can easily be installed in any automobile, and which is quickly changed from one purpose to the other.

I attain these objects with the mechanism 20 illustrated in the accompanying drawing, in which—

Fig. I is an elevation of my mat when used as a guard railing.

Fig. II is a plan view of Fig. I.

Fig. III is an end elevation of Fig. I as 25 seen along the line A—A.

Fig. IV shows the position of the guard railing in relation to the running board, when used as a foot mat.

Fig. V is a perspective view of an auxiliary guard rail.

Similar numerals refer to similar parts throughout the several views.

The body of an automobile is designated 35 by the numeral 1, the running board by 2, and the mat which also functions at times as a guard railing, by 3. The mat may be composed of any suitable material, the one in the drawing happens to be a fabricated 40 combination of steel and leather. By means of the cotter pins 4, one edge of the mat is hinged to the running board; the other edge is stiffened by a metal bar 5, and to the angularly bent ends of the latter are pivoted 45 the links 6. Attached to the ends of the links, by means of the knee joints 7, are the links 8, and the latter are hooked into the eyes 9 in the body of the automobile—suitable eyes may be formed of bolts with the 50 headed ends bent over as shown in Fig. II.

An auxiliary guard rail is provided in the shape of a rod 10 with notches 11 (Fig. V).

This rod is placed into the corresponding notches 12 in the links 6 and 8, and by this means even a thin package may be pressed 55 tightly against the mat and held securely in place. When not in use the rod 10 is carried between the spring clamps 13 on the metal bar 5.

In Fig. III the manner of folding the 60 links and the mat is clearly illustrated. First the link 8 is lifted off the eye 9 and folded against the link 6 in the direction of the arrow 14; then both links are folded against the mat in the direction of the arrow 15; thereupon the mat itself is folded against the running board in the direction of the arrow 16. The ensuing position is shown in Fig. IV.

Having thus described my invention it 70 will be seen that my objects have been accomplished, and, though I have shown the preferred form of construction, I reserve to myself the right to make minor changes, providing I do not violate the spirit and principle of my invention.

I claim.

1. In a device of the character described, the combination of an automobile having a running board, with a foot mat hingedly attached to the edge of the running board, said foot mat being capable of standing on edge at right angles to the running board, a knee-jointed link pivotally attached to each upper corner of the foot mat, an eye 80 attached to the automobile opposite each of said upper corners, said eye being adapted to support the other end of said link, notches in the upper edges of said links, and a rod extending throughout the full length of the 85 foot mat and reposing in the notches of the links in parallel relation to the mat.

2. In a device of the character described, the combination of an automobile having a running board, with a foot mat having one 90 edge hingedly attached to the running board, spring clamps attached to the edge of the foot mat opposite the hinges, and a rod of slightly greater length than the mat removably secured in the spring clamps.

Signed by me at Portland, Oregon, this 100
20th day of June, 1921.

CARL WILHELM SCHOPPE.
